EX

Design No. 13,421, dated November 14, 1882.

UNITED STATES PATENT OFFICE.

JOHN L. POPE, OF CLEVELAND, OHIO.

DESIGN FOR A CARRIAGE-STEP.

SPECIFICATION forming part of Design No. 13,421, dated November 14, 1882.

Application filed August 2, 1882. Term of patent 14 years.

To all whom it may concern:

Be it known that I, JOHN L. POPE, of Cleveland, in the county of Cuyahoga and State of Ohio, have invented and produced a new and original Design for Carriage-Steps, of which the following is a specification, reference being had to the accompanying photographic illustration, forming part thereof.

My present invention relates to a new design for carriage-steps; and it consists primarily in the use of raised bar-work to form in the center of the plate the figure of a star surrounded by six polygonal figures; and, secondarily, in certain other features of design, all of which will be hereinafter more particularly described and claimed.

It will be seen in accompanying photograph that the raised bars are so laid out as to form the outline of a star in the center of the plate, and around this star will be readily seen six hexangular figures, which I have marked with the letter *a*. Within the star formed by the bar-work I have shown a star-shaped ornament, *b*; but this may be omitted without changing the main feature of my new design. From the figures *b* the raised ornamentation extends around in various directions, crossing and recrossing and forming a number of many-sided figures, and near each corner extremity of the

step may be observed a figure nearly square 30 in appearance of outline, and it will be found designated by the letter *c*. At each corner of the step I have shown a corrugated-like angular piece and marked it with the letter *d*.

Instead of making the plate solid, as shown, 35 I may deem it desirable to cast it open between the polygonal figures or any of them, and in so doing I should not consider that I had materially deviated from the identity of the novel design shown herein.

What I claim as new, and desire to secure by Letters Patent, is—

1. A design for a carriage-step, consisting of a star and six surrounding and adjacent polygonal figures, all formed by raised bar-work. 45

2. A design for a carriage-step, consisting of a central star and six surrounding and adjoining figures, all formed of raised work, which extends outwardly, forming the figures *c*, with or without the corrugated ornamental pieces *d*, substantially as shown. 50

In witness whereof I have hereunto set my hand this 31st day of May, 1882.

JOHN L. POPE.

In presence of—

A. A. POPE,
C. M. COPP.
